DOOR LATCH

Daniel C. Johnson, Chapel Hill, N. C.

Application September 9, 1938, Serial No. 229,204

2 Claims. (Cl. 292—335)

My invention relates to vehicle doors and has among its objects and advantages the provision of an improved door latch.

An object of my invention is to provide a door latch designed to effectively hold the door in its closed position in which the latch is so designed as to compensate for wear. The latch embodies angularly related latch parts so designed as to eliminate rattling. I make use of a spring pressed latch bolt cooperable on a companion latch abutment or keeper for holding the door in its closed position. The keeper includes an inclined plane for retracting the latch bolt as the door is being closed. After closing the door, the latch bolt cooperates with the keeper for maintaining effective closing forces on the door, in addition to positively latching the door in its closed position. I provide the latch bolt with roller bearing mounts to facilitate shifting thereof. The bolt also includes a roller element for engagement with the inclined plane of the keeper.

In the accompanying drawing:

Figure 1 is an elevational view of a portion of the outer face of an automobile door and the associated jamb.

Figure 2 is a sectional view along the line 2—2 of Figure 1 illustrating the door in its closed position.

Figure 3 is a view similar to Figure 2 but illustrating the door in a partly closed position.

Figure 4 is a sectional view along the line 4—4 of Figure 2.

Figure 5 is a perspective view of the latch bolt.

Figure 6 is a perspective view of the keeper.

In the embodiment selected to illustrate my invention I make use of an automobile door 10 and a door jamb 12. Fragments of the door and jamb are illustrated in Figure 1. The door 10 includes the usual flange 14 arranged in overlapping relation with the jamb 12 when the door is closed. The door also includes a vertical frame member 16. These parts may be of conventional construction and need not be described in further detail.

The frame member 16 is recessed at 18 for accommodating the latch mechanism 20. The latch mechanism 20 comprises a latch bolt 22 slidable vertically between spaced guide members 24 and 26. The members 24 and 26 are positioned between plates 28 and 30, and the parts are connected into a unitary structure by screws 32 and 34. The screws 32 extend through openings in the plate 28 and have threaded relation with bores 36 in the members 24 and 26,

while the screws 34 extend through openings in the plate 30 and have threaded relation with the bores 36.

The latch bolt 22 is preferably rectangular in cross section and is provided with two rollers 38 arranged in rolling relation with the faces 40 of the members 24 and 26. The members 24 and 26 are provided with rollers 42 which have rolling relation with the faces 44 on the latch bolt 22. Rollers 38 and 42 function to permit easy movement of the latch bolt in addition to guiding the same in a vertical path.

To the face 46 of the jamb 12 I fixedly secure a keeper 48 through the medium of a screw 50. The screw 50 extends through a slot 52 in the keeper 48, which keeper is recessed at 54 to accommodate the head 56 of the screw. Thus the head 52 lies within the contour of the keeper, while the keeper may be shifted longitudinally in a horizontal direction for bringing its end 58 into precise relation with the latch bolt 22. The keeper 48 includes a second slot 60 for accommodating a screw 62 anchored in the same manner as the screw 50. The frame member 16 of the door is recessed at 64 for accommodating the keeper 48.

The face 58 of the keeper 48 is arranged at a slight angle to the vertical, while the latch bolt 22 includes an angular face 66 paralleling the end 58. The keeper 48 is recessed at 68 for partly housing a roller 70 arranged to have pressure relation with the face 66 of the latch bolt. Figure 2 illustrates the door in a closed position at which time the latch bolt is positioned in the rear of the keeper 48 and in pressure relation with the roller 70. The recess 64 communicates with a recess 72 within which I mount a block 74 through the medium of a screw 76, which screw may be of the same type and anchored in the same manner as the screw 50. The block 74 carries a roller 78 arranged to have pressure relation with the face 44 of the latch bolt. The recess 72 also accommodates the lower end of the latch bolt 22 with the parts arranged according to Figure 2.

Figure 3 illustrates the normal position of the latch bolt 22 when the door is opened. The latch bolt is urged downwardly through the medium of a spring 80 bent into the shape of a U, with one leg of the spring bearing against the upper end of the bolt 22 and the opposite leg made secure to the frame member 16 by a screw 82. The bolt 22 may be manually retracted against the tension of the spring 80 by a pull

line 84 which may be operably connected with any type of suitable handle (not shown).

In the position of Figure 3, the latch bolt 22 is restrained from relative downward movement by reason of a latch pawl 86. The pawl 86 includes a wedged shaped end 88 arranged to extend into a slot 90 in the latch bolt. The pawl 86 is pivotally mounted on a pin 92 anchored to the plates 28 and 30. I slot one end of the pawl 86 at 94 for accommodating one end of a shaft 96 having that end pivotally connected at 98 with the pawl. The pivotal connection 98 is offset laterally of the pivotal connection 92. The shaft 96 is slidably guided inside an opening 100 in the member 26. The opening 100 terminates in a larger diameter bore 102 within which I mount a compression spring 104. One end of the spring bears against the bottom 106 of the bore while the opposite end of the spring bears against a flange 108 formed on the shaft 96. The flange 108 has guiding relation with the bore 102 and the spring 104 urges the shaft 96 downwardly for pivoting the latch pawl 86 in the direction of the latch bolt 22.

Figure 3 illustrates the latch pawl 86 positioned within the slot 90 for restraining further downward movement of the latch bolt 22. According to Figure 3, the door 10 is closed by movement in the direction of the arrow 110 relative to the keeper 48. The lower end of the latch bolt 22 is provided with a roller 112 arranged to engage the inclined face 114 of the keeper. As the door is being pushed home the inclined face 114 will raise the latch bolt 22 as the roller 112 is advanced along the face. With the door substantially closed, the roller 112 passes over the high point 116 of the keeper to permit the latch bolt to fall downwardly in the rear of the keeper. The spring 80 imparts a rapid movement to the latch bolt so as to insure an immediate and positive latching relation between the parts. The inclined face 66 on the latch bolt 22 passes downwardly on the roller 88. The angular face 66 urges the door 10 to its closed position. The roller 78 bears against the opposite face of the latch bolt 22 so as to provide an effective backing therefor. It will thus be seen that the tapered end of the latch bolt will be wedged between the rollers 78 and 79. The angular face 66 compensates for wear between the parts so as to provide a latch which eliminates rattling of the door.

As the door is advanced to a closed position, angular face 114 has camming relation with the curved end 118 of the shaft 96 to move the shaft upwardly. Such upward movement of the shaft pivots the latch pawl 86 to the position of Figure 2 and in the clear of the latch bolt 22.

In opening the door, the latch bolt 22 is lifted upwardly sufficiently far to bring the roller 112 in the clear of the end 58, thus permitting the door to be swung outwardly. With the latch bolt 22 lifted sufficiently far to clear the keeper 48, the slot 90 is positioned somewhat above the wedged end of the latch pawl 86. As soon as the end 118 is moved out of camming relation with the face 114, the spring 104 moves the shaft 96 downwardly for pivoting the pawl 86 in the direction of the latch member 22. The end of the latch pawl is maintained in pressure relation with the adjacent face 44 of the latch bolt so as to insure entrance of the pawl into the slot 90.

The movably related parts operate without frictional relation. The spring 80 effectively holds the latch bolt in the position of Figure 2. 75

The angularity of the face 66 is slight so as to prevent the latch bolt from being cammed upwardly through an outward pull on the door. However, the angularity is sufficient to compensate for wear. The roller 78 exerts pressure in one direction while the roller 79 and some of the rollers 38 and 42 exert pressure in the opposite direction. Thus the latch bolt 22, in the position of Figure 2, is characterized by a three-point contact which supports the bolt in a sturdy manner. The latch bolt lifts easily up the inclined face 114, thus permitting closing of the door with the application of relatively small forces. The door need not be slammed heavily to consummate latching thereof. A gentle push will bring the door to a completely closed position. At the same time, the latch bolt is characterized by a quick action which insures positive latching. A considerable reach of the latch bolt 22 extends across and below the end 58 of the keeper. This relation prevents accidental unlatching in the parts.

The latch bolt is completely housed inside the contour of the door proper. The mechanism is easily installed in the recess 12, while the latch mechanism is easily disassembled because of the detachable connection between the plates 28 and 30 with respect to the members 24 and 26.

What I claim is:

1. In a door latch, a relatively fixed keeper having a roller element, a guide, a latch bolt slidably in said guide and spring pressed to be projected behind the keeper in engagement with said roller element, a second roller element mounted on a fixed support for engagement with the bolt on the side opposite said first-mentioned roller element but spaced from the latter longitudinally of the bolt, roller means interposed between said bolt and said guide for guiding the bolt, some of said roller means being located on the same side of the bolt as said second roller element but spaced from said first-mentioned roller element longitudinally of the bolt in a direction opposite the spacing of said second roller element, and said bolt having a cam face engageable with said first-mentioned roller element for pressing the bolt against said second roller element and said some of said roller means.

2. In a door latch, a relatively fixed keeper having a cam face, a spring projected and manually retractable bolt slidably mounted in the latch and arranged to engage said cam face and ride thereon to a retracted position and then project behind the keeper as the door is moved to a closed position, said latch bolt being provided with a notch extending inwardly and axially of the bolt, a pawl pivoted to said latch arranged to enter said notch when said bolt is moved to a partially projected position, a shaft slidably in said latch and having one end pivotally connected with said pawl, resilient means acting on said shaft for urging the other end of the shaft into the path of said cam face, said bolt, in said partially projected position, engaging said cam face in advance of said shaft to be moved to a partially retracted position and position said notch clear of said pawl, said other end of said shaft resting on said cam face in the closed position of the door to hold the pawl away from the bolt, said notch being so located as to receive the pawl in the open position of the door to support the bolt in said partly projected position in the path of said cam face.
